UNITED STATES PATENT OFFICE

2,474,668

FURNITURE

Roger C. Herbolsheimer, Garrett, Ind.

Application January 9, 1947, Serial No. 720,976

5 Claims. (Cl. 155—196)

1

This invention relates to improvements in furniture, particularly stools and the like.

An object of the invention is to afford stools that are light in weight, of great strength, attractive in appearance and low in cost of manufacture.

Another object of the invention is to shape the seat and the legs of a stool so they have interlocking connection with each other and are held rigidly in place when the legs are spread outwardly and secured by a brace.

Other objects and advantages of the invention appear in the following description.

An illustrative embodiment of the invention is shown in the accompanying drawings, in which:

Fig. 1 is a perspective view of a structure in which the invention is incorporated;

Fig. 2 is a fragmentary cross-sectional view showing the interlocking connection of the seat and one of the legs; and

Fig. 3 is a fragmentary perspective view of the upper end portion of the leg structure.

The illustrative embodiment of the invention consists of a stool structure in which are assembled, and connected together, a seat 3, legs 4 and a leg brace 5.

The seat is formed of sheet metal shaped to have a peripheral downturned annular flange 6, around the lower marginal part of which is formed an exterior annular bead 7 and a corresponding interior channel 8. In the flange 6 are punched openings 9 exposed to the exterior, and coincident therewith are corresponding inset portions constituting stirrups 10.

The legs preferably are formed of channel-like metallic strips, the lower end portions of which are suitably shaped so the legs, when assembled with the seat, spread outwardly. The upper end portion of each leg 4 has opposite side flanges 11 the tops of which terminate abruptly to provide stops 12, and the wall 13 of the leg, intervening between the side flanges, extends upwardly beyond the stops to provide a tongue 14.

At a point spaced suitably below the stops 12, the wall 13 is bulged outwardly to form a transversely disposed bead 15. The arrangement of the stops, tongue and bead is such that when the tongues 14 are inserted into the stirrups 10 the openings 9 in the seat flange are closed, the stops bear against the lower edges of the stirrups and the beads 15 project into the channel 8, thus establishing interlocked connections between the legs and the seat. The brace 5, preferably in the form of a hoop, is encompassed by the group of legs and secured thereto by rivets or bolts 16.

2

to hold the legs properly spread apart from each other thereby binding the interlocked connections between the seat and legs firmly in place. In this manner the various parts are shaped, assembled, interlocked and stressed to afford a rigid durable stool structure.

Variations from the particular construction above disclosed may be resorted to by the exercise of skill in the art, without departure from the spirit or scope of the invention.

What I claim is:

1. In a stool structure, a seat having a peripheral downturned flange provided with inset portions constituting stirrups and an interior annular channel in its lower part, legs supporting said seat, the upper end portion of each leg having side flanges providing stops, a tongue extending upwardly beyond the stops, and an exterior transverse bead located below said stops, the arrangement being such that when the tongue is inserted into a corresponding stirrup the stops bear against the lower edge thereof and the bead projects into said channel, thus establishing an interlocking connection between the seat and leg, and a brace secured in connection with the legs to spread the lower parts thereof and cause binding of said interlocking connections.

2. A stool structure consisting of a sheet metal seat having a peripheral downturned flange provided with an interior annular channel, stirrups on the inner wall of said flange, legs supporting said seat, the upper ends of said legs being shaped to have stops on the sides thereof and a tongue extending upwardly beyond said stops, beads transversely disposed exteriorly on said legs, the arrangement of the stops, tongues and beads being such that when the tongues are inserted into the stirrups correspondingly the stops bear against the lower edges thereof and the beads project into said channel, thus to provide interlocking connections between the legs and seat, and a brace encompassed by the legs and secured thereto whereby to spread the legs outwardly and bind the interlocking connections between the seat and legs.

3. A metallic stool structure in which is included a seat, legs and a leg brace, said seat having a peripheral downturned flange provided with interior stirrups and an interior annular channel, the upper end portions of said legs being provided with stops, tongues and exterior beads arranged so that when the tongues are positioned correspondingly in said stirrups, the stops engage the lower edges of said stirrups and the beads project into said channel, thus establishing inter-

locking connections between the seat and legs, and said leg brace being attached to said legs to hold same in interlocking position.

4. A stool constructed of sheet metal and having a seat provided with a peripheral downturned annular flange, said flange having inset portions thereof constituting stirrups and an interior channel in its lower marginal portion, legs for supporting said seat provided with side flanges constituting stops, upwardly extending tongues and outwardly extending beads, said stops and tongues having engagement with said stirrups, and said beads having engagement with said annular flange by protrusion into said channel when the legs and seat are assembled, and a brace secured in connection with the lower portions of said legs to hold same in outspread position, the arrangement being such that the legs and seat are interlocked and bound together when the brace is in place.

5. A stool consisting of a seat having a peripheral downturned flange provided with stirrups on its inner wall and a channel adjacent thereto, legs to support the seat provided with tongues and stops engageable with said stirrups and exterior beads engageable in said channel, whereby to interlock the legs and seat when in place, and a brace connecting said legs adapted to hold same outspread thus to secure the legs and seat firmly 10 in their interlocked connections.
